COLLAPSIBLE A-FRAME STRUCTURE FOR
SHOVELS, CRANES, OR THE LIKEStanley B. Elgh, Milwaukee, Wis., assignor to
Koehring Company, Milwaukee, Wis., a corpora-
tion

Application March 11, 1936, Serial No. 68,316

9 Claims. (Cl. 212—59)

In the art of excavating machinery, particularly cranes of the shovel, clamshell and dragline types, there is customarily used as a part of the machine structure a so-called A-frame, over the upper portion of which certain of the operating cables of the machine by which the elevation of the boom and operation of other mechanism of the machine is accomplished are trained. Upon the height of the A-frame aforesaid largely depends the maximum height or elevation to which the booms of different types of machines aforesaid may be raised for performing their customary functions.

It is desirable that the A-frame structure of the machine be designed so as to be as low as possible in order that the excavating machine in travel may pass underneath relatively low bridges or other obstructions. On the other hand, since the height of the A-frame is required to be varied for different lengths of booms, and, by reason of the necessity of elevation of these different lengths of booms to various heights, it is desirable to provide some kind of A-frame construction that will accommodate such variation of boom heights in the practical use of the machine.

Heretofore, it has been necessary, where different lengths of booms are used beyond certain maximums, that the A-frame structure of the machine be designed especially for the accommodation of the particular length of boom, and machines have been constructed under such conditions with A-frames of such heights that they must be shipped or must travel with the A-frame removed or taken down, the same later to be re-erected or set up, all of which makes for a troublesome, times-taking and expensive operation, especially if the work has to be done out on the field away from the factory.

The primary object of this invention has been to do away with the difficulties heretofore experienced along the above lines, by providing what may be characterized as a combination A-frame structure wherein there are used a main or low-A-frame having associated therewith a high or auxiliary A-frame. The high A-frame is preferably carried by the low A-frame in such a manner that when the low A-frame is employed the auxiliary A-frame is out of use and out of the way, but the arrangements of the invention as herein set forth are such that the high or auxiliary A-frame may be very quickly and easily set up in operative position in relation to the low A-frame so that if an elevation of the boom greater than that permitted by the use of the low frame is desired, as for handling a particular

job, the advantage of the high frame may be obtained very quickly. Likewise, the same is true when the high A-frame is required to be used upon the substitution of a long boom for a shorter boom on the crane, or when the crane is equipped with a much longer boom than is designed to be used when the low A-frame structure is availed of.

An object of the invention resides in the designing of the main and auxiliary A-frames referred to in such a way that the hoisting mechanisms of the crane may be availed of for the handling of the high A-frame as for elevating the same to its operative position ready to be used, and for facilitating the lowering of said frame, thereby not necessitating the employing of separate machinery for this purpose, something required heretofore because of the weight of the parts of A-frames according to previous designs.

Another object of the invention may be said to comprise the designing of the frame hereof in such a manner that it may be quickly converted from a low A-frame type of machine to a high A-frame type of machine, permitting of the employment upon a single unitary machine of different lengths of booms and permitting the variation in the elevated or working height of any boom with which the machine is equipped. The standard power actuated parts of the machine are availed of, as previously suggested, in the manipulation of the auxiliary A-frame utilized, in rendering same operative or collapsing the same to cause it to assume an inactive position, under which conditions the low A-frame is resorted to for lowering or elevating the peak of the boom associated with the crane body.

Other and further objects of the present invention will become apparent from the following description and accompanying drawings, in which—

Figure 1 illustrates a side elevation of the stationary A-frame of a shovel, crane, or the like, provided with an auxiliary collapsible high A-frame, a portion of the turntable and side frame being also illustrated in this figure to show the location of the parts more clearly.

Figure 2 is an elevational view of the stationary high A-frame as illustrated in Figure 1, the view being taken in the direction of arrows 2—2 of Figure 1.

Figure 3 is a front view of a portion of the compression members of the high A-frame, taken in the direction of the arrows 3—3 of Figure 1, illustrating more clearly the position of the spacer.

member and cable connections of the high A-frame.

Figure 4 is a view similar to Figure 1, showing the high A-frame in collapsed position.

- 5 Figure 5 is a perspective view of a portion of a shovel showing more clearly the position of the high A-frame with respect to the other structure of the machine, the high A-frame being shown in collapsed position.
- 10 Referring to the drawings, and especially to Figures 1 to 3, and 5, A indicates the stationary A-frame as employed in shovels, cranes, or like excavating machinery, which comprises the rear A-frame or tension members 1 and 2 which are
- 15 connected by the lower A-frame shaft 3 to compression members 4 and 5 in a manner clearly shown in Figure 5. The ends of the tension and compression members opposite the lower A-frame shaft 3 are connected to the turntable 6 of the machine at 7 and 8, as will be obvious from Figure 1. In this manner a rigid and stationary A-frame structure is provided to form a support for a sheave 9 over which the boom hoist cable 10 is trained. One end of the boom hoist cable 10 is connected to boom hoist drum 11 mounted on shaft 12 and provided with a boom hoist clutch 13 to permit operation of the boom hoist cable drum 11 for winding the boom hoist cable to effect raising and lowering of the boom B of the machine.

20 Mounted upon shaft 12 is a rear hoist drum 14 to which the dipper hoist cable 15 is connected, and usual clutching instrumentalities are provided for the rear hoist drum 14 to effect the 25 operation of the same for raising or lowering the dipper stick.

25 The above structure represents the conventional structure employed in excavating machinery today, and it will be seen that the position 30 of the sheave 9 with regard to the boom pivot point C cannot be varied in view of the stationary arrangement of the A-frame A, and, in the event a long boom is used in connection with mechanism described herein, it will be necessary to provide a machine with an A-frame of a higher construction to permit the desired height of lift for the boom. Such higher A-frame construction, however, extends considerably above the remaining parts of the machine and will prevent passing of the machine underneath low bridges or other obstructions. It was therefore necessary heretofore to disconnect such high A-frame to permit the machine to pass underneath obstructions, as outlined above.

35 To overcome the above difficulties, I provide a stationary low A-frame construction A, as referred to above, which is provided with a collapsible auxiliary or high A-frame structure D, as clearly illustrated in Figures 1 to 3. The auxiliary A-frame D comprises rear frame members or tension members 16 and 17, and compression members 18 and 19. The members 16 and 17, and 40 18 and 19, are pivotally connected by an upper A-frame shaft 20. The opposite ends of the tension members 16 and 17 are pivotally connected to the lower frame shaft 3 which forms a part of the lower A-frame structure A as previously described. The free ends 18a and 19a of the compression members 18 and 19 are connected to compression guide members 21 by means of pins 22. The compression guide members 21 are secured to and form a part of the compression members 4 and 5 of the lower A-frame A.

45 The upper frame shaft 20 is provided with a sheave 23 for the boom hoist cable, and an A-

frame yoke 24 pivotally connected to the upper frame shaft 20 is arranged to carry a sheave 25 for the reception of other portions of the boom hoist cable, the free end of which is secured to the auxiliary or high A-frame, as clearly seen at 5 26 in Figure 5. While the A-frame yoke of the auxiliary A-frame D, as seen in Figure 5, is provided with a single cable sheave 25, the yoke member 24, as shown in Figure 1, is provided with another cable sheave 27 which is utilized in 10 case the auxiliary A-frame is used in connection with a crane.

50 Arranged between the compression members 18 and 19 is a spacer member 28 secured to brackets 29 and 30 welded to the aforesaid compression members. The spacer member 28 maintains the compression members 18 and 19 in properly spaced relation in regard to each other when the same are disconnected from the compression guide members 21. A cable 31 is connected to the spacer member 28 and the compression members 18 and 19 as clearly seen at 32 and 33 in Figure 3 to form a loop to which an A-frame hoist cable 34 is connected, for purposes explained 20 later on.

55 When the auxiliary A-frame D is arranged in the position shown in Figure 1, the boom hoist cable 10 will extend from the hoist cable drum 11 over sheaves 9 and 23, as clearly seen in Figure 1, and with the parts in this position a longer boom may be employed in connection with this machine, while the height of lift of the same is not reduced, which would be the case if a low A-frame were employed. If it is desirable to operate the machine only with the low A-frame A in 30 operation, or if the machine is to be passed underneath low obstructions, the high A-frame D may be collapsed in a manner apparent from the following description.

60 The boom B of the machine is lowered until the bucket mounted on the dipper stick touches the ground and supports the boom. Now a portion of the rear end 15' of the dipper hoist cable 15 is removed from the rear drum 14 by taking off several turns of the rear end of the cable 15. 45 The free end of cable 34 connected to the compression members 18 and 19, previously described, is swung around the right-hand portion of the drum 14 several times, from which a portion of cable 15 has been removed, and the end of the 50 cable 34 is now anchored by means of anchor 15' to drum 14. The slack in cable 34 is now taken up by rotating drum 14, and the pins 22, which secure the compression members 18 and 19 to the compression guide member 21, are removed, 55 whereupon cable 34 is released from drum 14 by unwinding the same therefrom upon release of the brake of said drum. The auxiliary or high A-frame D will thereupon collapse to the position shown in Figure 4. The sheave 23 will 60 thereby be moved out of contact with the boom hoist cable 10, as clearly seen from this latter figure. Upon completion of the lowering of the frame, the end of the cable 34 attached to rear drum 14 is now disconnected therefrom. 65

65 The boom B may now be raised and the dipper stick and bucket operated in the usual manner, and in view of the fact that the high A-frame D is now in its lower position, and the over-all height of the machine is materially reduced, the same may now be passed underneath low bridges or other obstructions, or the machine may be operated with the low A-frame, in the same manner as when the auxiliary or high A-frame D was in operative position; however,

the height of lift of the boom will now of course be considerably reduced.

It should here be noted that when the brake mechanism of the dipper hoist cable drum has been released, the high A-frame will automatically collapse in view of its own weight, and the collapsing action of the frame may be controlled by applying the last mentioned brake slightly, to produce a slow and gradual lowering of the auxiliary frame. Should the auxiliary frame not collapse in view of its own weight, which may occasionally happen, tensioning of the cable 10 momentarily engaging clutch 13 will force the A-frame out of its connection with the compression member guides 21 and in this way manual labor to free the compression members 18 and 19 from their respective compression member guides is entirely eliminated.

Supporting brackets 35 and 36 are provided on the compression members 4 and 5 of the low A-frame to limit the downward movement of the tension members 16 and 17 of the auxiliary A-frame and to support the latter in a position substantially parallel to the upper surface of the turntable 6.

After the obstruction has been passed, or if a higher lift of the boom is desirable, the auxiliary A-frame may be again raised to operative position, as will be described in the following:

30 The free end of cable 34 is again connected to the right-hand side of drum 14 by means of anchor 15', and upon rotation of drum 14 cable 34 is wound upon said drum, thereby raising the auxiliary frame D from its lowered position to its raised position until the compression members 18 and 19 slide upon the upper surface of the compression member guides 21 to which they may be secured by inserting pins 22.

After collapsing the auxiliary frame, as previously described herein, and after disconnection of cable 34 from drum 14, the machine may be operated with the lower A-frame in position for performing the hoisting functions of the boom and dipper stick. However, if the machine is 45 only to be passed underneath some obstruction and immediately used after passing the same, with the auxiliary frame in operative position, cable 34 need not be disconnected from drum 14, as the raising operation of the auxiliary A-frame 50 will have to be performed as soon as the obstruction is passed. In such case the boom, which is supported by lowering the bucket to the ground, as previously mentioned, may be raised out of contact with the ground by operating boom hoist cable drum 11 and after the obstruction has been 55 passed it will be necessary to unwind a portion of the boom hoist cable 10 to permit the raising of the auxiliary A-frame as hereinbefore described.

60 A sheave 40 mounted on the lower A-frame shaft 3 is provided for supporting the cable 34 in position above the connecting member 31, as clearly seen in Figure 1, as is necessary for permitting a raising or lowering of the auxiliary frame, as set forth above.

The horizontal guide portions 21a of members 21 extend somewhat forwardly of the points of connection 8 between the turntable structure 6 and the compression members 4 and 5 of the lower A-frame so as to guide the compression members 18 and 19 upon collapsing of the auxiliary A-frame, thereby not to interfere with any parts of the lower A-frame and turntable structure, as clearly seen from Figures 4 and 5.

75 Having thus described my invention, what I

claim as new and desire to secure by Letters Patent of the United States, is—

1. In a crane of the class described, in combination, a crane body, a boom pivoted thereto for raising and lowering movement, hoist cable 5 mechanism for raising and lowering the boom carried by the body, a combination A-frame structure on the body including a low A-frame and a high A-frame superposed upon the low A-frame, both the low A-frame and the high A-frame having means to cooperate with the hoist cable means aforesaid, and means for supporting the high A-frame in a high operative position relatively to and on the low A-frame, and for supporting said high A-frame in a collapsed or inoperative position on the low A-frame. 15

2. In a crane of the class described, in combination, a crane body, a boom pivotally mounted thereon, hoist means for raising and lowering said boom, an A-frame structure cooperating 20 with said hoist means and carried by the body and comprising a stationary part and a superposed collapsible part, means for establishing cooperation between either the stationary part or the superposed collapsible part and the hoist 25 means, operating mechanism on the body for cooperation with excavating means carried by the boom, and instrumentalities operable by the last mentioned means for raising the superposed A-frame to an operative position on its associated 30 A-frame.

3. In a crane of the class described, in combination, a crane body, a boom pivotally mounted on said body, an A-frame structure comprising a main A-frame stationary on the body, an auxiliary collapsible A-frame structure pivotally mounted on said main A-frame, removable means between the main A-frame and the collapsible A-frame for holding said collapsible A-frame in raised position, and instrumentalities cooperative 35 with the main collapsible A-frame and boom for raising and lowering the collapsible A-frame. 40

4. In a crane of the class described, in combination, a crane body, a boom pivotally mounted on said body, an A-frame structure comprising a main A-frame stationary on the body, an auxiliary collapsible A-frame structure pivotally mounted on said main A-frame, removable means between the main A-frame and the collapsible A-frame for holding said collapsible A-frame in raised position, instrumentalities cooperative 45 with the main A-frame and boom for raising and lowering the collapsible A-frame, and means for controlling collapsing of the collapsible A-frame under its own weight upon removal of said removable means to enable the collapsible A-frame 50 to assume an inoperative position out of cooperation with said instrumentalities. 55

5. A machine as set forth in claim 4, combined with guiding means on the main A-frame cooperative 60 with the collapsible A-frame for guiding the latter with respect to its movement relatively to the main A-frame.

6. In a crane of the class described, in combination, a crane body, a boom movably mounted thereon, a main A-frame on the body, a collapsible A-frame on the body, means supporting the collapsible A-frame on the main A-frame, and hoisting means for raising and lowering the boom cooperative with either the main A-frame or the 65 collapsible A-frame, together with means for holding the collapsible A-frame in an operative position on the main A-frame when said hoisting means coacts with the collapsible A-frame. 70

7. In a crane of the class described, in com- 75

- 5 bination, a crane body, a boom thereon, means for raising and lowering the boom, comprising cable instrumentalities connected with the boom, a main frame having a sheave to guide the cable instrumentalities, and an adjustable A-frame structure associated with the main frame and also having a sheave to guide the cable instrumentalities, whereby through variation in the height of the A-frame, variation in the height of 10 the adjustment of the movement of the boom may be effected, and supporting means for the adjustable A-frame to hold the same elevated so its sheave will guide the cable instrumentalities, said supporting means being operable to allow 15 lowering of the adjustable A-frames to a position with its cable sheave not guiding the cable means.
8. In a crane of the class described, in combination, a crane body, a boom thereon designed to have the boom peak thereof raised and lowered for the purpose described, hoisting instrumentalities for said boom, to peak the same up and down, comprising cable means, and alternatively usable structures on the crane body cooperative with the said cable, and means for adjusting the 20 position of such structures vertically whereby to vary the maximum amount of lifting of the boom as may be required by varying conditions of service, such as require different elevations of the boom to enable the crane to perform effective work, the alternatively usable structures including a rigid main A-frame having sheave means to coact with the cable means, an auxiliary A-frame structure having sheave means adapted to be shifted into and out of engagement relative 25 to the cable means by which the boom peak is raised and lowered.
9. In a crane of the class described, in combination, a crane body, a boom thereon designed to have the boom peak thereof raised and lowered 5 for the purpose described, hoisting instrumentalities for said boom to peak the same up and down, comprising cable means, and alternatively usable structures on the crane body cooperative with the said cable, and means for adjusting the 10 position of such structures vertically whereby to vary the maximum amount of lifting of the boom as may be required by varying conditions of service, such as require different elevations of the boom to enable the crane to perform effective 15 work, the alternatively usable structures including a rigid main A-frame having sheave means to coact with the cable means, an auxiliary A-frame structure having sheave means adapted to be shifted into and out of engagement relative 20 to the cable means by which the boom peak is raised and lowered, the auxiliary A-frame being supported on the main A-frame, lower cable means connected to the auxiliary A-frame whereby it may be elevated to an operating position wherein 25 its sheave means coacts with the first mentioned cable means to raise the point of support of this cable means to increase the maximum lift of the boom when the cable means is cooperating with the sheave means of the auxiliary A-frame, and 30 means to hold the auxiliary A-frame stationary when elevated.

STANLEY B. ELGH.
